UNITED STATES PATENT OFFICE.

HARRY VISSERING, OF KENILWORTH, ILLINOIS.

DEVICE FOR CONTROLLING AND OPERATING LOCOMOTIVE WHISTLES.

Application filed March 27, 1926. Serial No. 97,991.

The invention relates to devices for controlling and operating locomotive whistles.

The objects of the invention are to provide an improved whistle-operating device which is adapted for operation on the extreme front end of the locomotive and in front of the smoke-stack, so that the sound may be efficiently projected; in which the steam valve and the pneumatic piston for controlling the steam valve are mounted in a single casing, so that the cylinder for the piston will be heated by the steam to prevent freezing of the parts; in which provision is made for manually operating the valve when desired; in which provision is made for cutting off the supply of steam to the valve casing when repair of the valve becomes necessary; and which is connected to receive superheated steam from the throttle valve casing at the front of the locomotive. Other objects of the invention will appear from the detailed description.

The invention consists in the several novel features hereinafter set forth and more particularly defined by claims at the conclusion hereof.

In the drawings: Fig. 1 is a diagrammatic view of a locomotive equipped with the invention. Fig. 2 is a longitudinal section through the front end of the locomotive. Fig. 3 is a section on line 3—3 of Fig. 2. Fig. 4 is a section through the casing for the steam valve for the whistle and the pneumatic device for operating it. Fig. 5 is a section on line 5—5 of Fig. 4. Fig. 6 is a plan of the device shown in Fig. 4, parts being shown in section. Fig. 7 is a perspective of the pivoted operating member between the stems of the steam-valve and the pneumatically operated piston. Fig. 8 is a detail perspective of the arm for shifting said member.

The invention is exemplified in connection with a locomotive 10 which is provided with the usual engineer's cab 11 at its rear and a smoke stack 12 adjacent its front end. The locomotive is of that type in which a superheater is used for the steam delivered to the engine cylinders, as exemplified by a superheater comprising a header 13 located in the front bulk-head 14 of the boiler. A pipe 15 delivers steam from the dome of the boiler into the header 13. Superheater pipes 16 are connected to the header 13 and are heated by the boiler, as well understood in the art.

Two outlet pipes 17 are connected to the header 13 and extend around the sides respectively of the smoke-stack 12 to the inlet chamber 19 of a throttle casing 18. A throttle valve 20 is vertically slidable in the casing 18 to control the supply of steam to an outlet chamber 21, to which are connected a pair of pipes 22 for delivering steam to the engine cylinders. The throttle valve 20 is operable by a crank 23 on a shaft 24. The upper portion of the throttle casing is disposed outside of the front end of the boiler, and shaft 24 extends outwardly to one side of the casing and is there connected by any suitable means to a lever in the locomotive cab.

A casing 26 is disposed adjacent the front of the locomotive boiler and in front of the smoke stack, and this casing supports the steam whistle 27 which may be of any suitable construction and contains a valve 28 for controlling the delivery of steam for the operation of the whistle and also contains the pneumatic device for operating said valve. The whistle 27 is supported from the casing 26 by an elbow 29 which has its upper end connected to discharge steam into the whistle and its lower end connected to a steam outlet 30 of casing 26. An admission chamber 31 is formed in the lower portion of casing 26 and this chamber is connected to receive steam from the throttle casing 18 through a pipe 32 which is connected to the lower end of chamber 31 by an elbow 33 which is connected to receive steam from the admission chamber 19 of the throttle casing. Chamber 31 is offset laterally and a cut-off valve 34 is mounted in the casing of steam valve 28. This valve is adapted to close against seat 35 when it is desired to prevent the delivery of steam to the whistle, for example, if a repair should be necessary to the steam valve. From chamber 31, the steam flows through a duct 31^a to a valve 28 which is adapted to close against a seat 36 and to control the delivery of steam into the outlet chamber 37 of the casing, which is connected to deliver steam to the whistle. Valve 28 is horizontally slidable, being provided with a stem 39, one end of which is slidable in a cap 38 which is screw-threaded to the casing 26, and the other end of which is slidable, as at 40, in the inner wall of chamber 37 of casing 26. The inner end of stem 39 projects into a recess 41 formed in

100
105
110

the top of the casing. A spring 42 is applied to hold valve 28 normally closed.

In practice, it is desirable to provide for the pneumatic and manual control of the valve 28, and for this purpose a member 43 is pivoted on a bolt 44, which is held in side walls 45 of the recess 41. This member is provided with a pendent abutment 46 which is adapted to engage the inner end of the stem 39 of the steam valve 28. This member is operable from the locomotive cab 11 by means of an arm 47 which is also pivoted on pin 44 and is adapted to engage an abutment 48 on member 43 when the arm is pulled rearwardly, and said member is free to swing independently of the arm when the member is operated by the pneumatic control. A rod 49 extends rearwardly from the upper end of arm 47 to a suitable lever system in the cab, so that, when the rod is pulled rearwardly, it will operate arm 47 which will impinge against abutment 48 and swing abutment 46 forwardly to open the valve 28.

The pneumatically operated controlling device for the steam valve comprises a piston 50 which is slidably mounted in a cylinder 51 formed in a head 52 which is removably secured to, and forms a part of, casing 26. A stem 53 is attached to the piston 50 and extends forwardly into position to engage the rear face of abutment 46, so that, when the piston is operated forwardly in its cylinder, stem 53 will operate abutment 46 forwardly against the rear end of valve stem 39 to open valve 28 and admit steam to the whistle. A pipe 54, which is adapted to deliver air under pressure into the cylinder 51 to operate the piston 50, leads from the head 52 to an air controller valve 55 which is located in the cab and may be of any suitable construction to control the delivery of air from a compressed air reservoir to the cylinder 51 and to exhaust the air from the cylinder when the valve 28 is to be closed.

When it is desired to pneumatically control the valve 28 for the steam whistle, the engineer will manipulate valve 55 to cause air under pressure to enter cylinder 51 which will force the piston 50 forwardly and operate member 43 to shift stem 39 of valve 28 forwardly to cause steam to pass to the whistle. When the air pressure is cut off at valve 55 and there exhausted, piston 50 will be retracted by the force of spring 42. When it is desired to manually shift the valve 28, the operator will manipulate the lever to pull rod 49 rearwardly which will swing member 43 to operate valve 28 independently of the pneumatic piston and its stem. In the operation of the valve 28 by the piston 50 through member 43, arm 47 remains stationary, so that its connection with the cab is not shifted.

The invention exemplifies controlling

mechanism for a steam whistle in which the casing for the whistle valve is mounted with the whistle at the front end of the locomotive where the sound produced by the whistle is not interfered with by the elements rearwardly thereof. By providing this casing at the front of the locomotive, and providing it with a pneumatically operated piston, it becomes possible to dispense with the steam connections between the casing or medial or rear portion of the boiler, which is a desideratum in locomotive practice. The invention also exemplifies a construction in which the casing for the whistle valve and pneumatically operated piston is connected to receive superheated steam from the throttle casing in front of the boiler to make it possible to utilize steam connection of minimum length. The whistle, steam valve, and operating piston may be conveniently mounted as a unit adjacent the front end of the boiler. The device as a whole is simple in construction and efficient in operation.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. The combination of a locomotive, a steam whistle, a casing to which the whistle is connected, mounted directly upon the locomotive shell and in front of the smokestack, a valve for controlling the supply of steam to operate the whistle, mounted in said casing, a connection disposed within the shell for delivering steam into said casing and to said valve, and means controlled from the cab for opening the steam valve.

2. The combination of a locomotive, a steam whistle, a casing to which the whistle is connected, disposed directly upon the locomotive shell and in front of the smokestack, a valve for controlling the supply of steam to operate the whistle, mounted in the casing, a pipe for delivering steam into said casing and to said valve, said pipe being disposed within the locomotive and having one end thereof extending through the shell and operating to support the casing, a fluid-pressure operated piston, mounted in said casing and adapted to open the valve, and means for controlling the piston from the cab.

3. The combination of a locomotive, a steam whistle, a casing to which the whistle is connected, mounted on the front end of a locomotive and in front of the stack, a valve in said casing for controlling the supply of steam to operate the whistle, a throttle valve for the locomotive comprising a casing mounted adjacent the front end of the loco-

motive, and a pipe connection for delivering steam from the throttle casing to the valve casing, and means to operate the steam valve from the cab.

5 4. The combination of a locomotive, a steam whistle, a casing to which the whistle is connected, mounted adjacent the front end of a locomotive and forwardly of the stack, a valve in said casing for controlling the supply of steam to operate the whistle, a superheater mounted in the front end of the locomotive, a connection for delivering steam from the superheater to the valve casing, and means to operate the steam valve from the cab.

5 5. The combination of a locomotive, a steam whistle, a casing to which the whistle is connected, a valve for controlling the supply of steam to operate the whistle, slidably mounted in the casing and provided with a stem, a fluid pressure operated piston slidably mounted in the casing and provided with a stem, said stems being independent of each other so that the valve and piston may be operated independently of each other; and a device for manually operating the steam valve extended between the contiguous ends of the stems, so that the steam valve may be operated by the piston-stem through said device and independently by

6 6. The combination of a locomotive, a steam whistle, a casing to which the whistle is connected, a valve for controlling the supply of steam to operate the whistle, slidably mounted in the casing and provided with a stem, a fluid pressure operated piston slidably mounted in the casing provided with a stem, said stems being independent of each other so that the valve and piston may be operated independently of each other; and a device for manually operating

the steam-valve comprising a member between the contiguous ends of the stems, so that the valve may be operated by the piston-stem through said member and independently by said member, and a lever having a one-way connection to said member.

7. The combination with a steam whistle, of a casing to which the whistle is connected, a connection for delivering steam into the casing, a valve for controlling the supply of steam to operate the whistle, said valve being horizontally slideable in the casing, a fluid pressure operated device comprising a cylinder in the casing and a horizontally slideable piston in the cylinder adapted to open the steam valve, the casing being provided with a steam chamber adjacent the cylinder so it will be heated by the steam, and a cut-off valve in the casing and at one side of the slideable valve.

8. The combination with a steam whistle, of a casing to which the whistle is connected, a connection for delivering steam into the casing, a valve for controlling the supply of steam to operate the whistle, means for controlling the steam valve from the cab of the locomotive, and a cut-off valve in the casing.

9. The combination with a steam whistle, of a casing to which the whistle is connected, a connection for delivering steam into the casing, a valve for controlling the supply of steam to operate the whistle, a fluid pressure operated device for shifting the valve, mounted in the casing, the latter being provided with a receiving chamber, and a cut-off valve between the receiving chamber and the steam valve.

Signed at Chicago, Illinois, this 4th day of December, 1925.

HARRY VISSERING.
